UNITED STATES PATENT OFFICE.

STATES LEE LEBBY, OF CHARLESTON, SOUTH CAROLINA.

HYDROPLANE-BOAT.

1,312,036.

Specification of Letters Patent.

Patented Aug. 5, 1919.

Application filed January 16, 1919. Serial No. 271,407.

To all whom it may concern:

Be it known that I, STATES LEE LEBBY, a citizen of the United States, and resident of Charleston, S. C., have invented certain new 5 and useful Improvements in Hydroplane-Boats, of which the following is a specification.

My invention relates to boats and aims to provide a construction of boat to be propelled by power or made to move over the water at high speed with the least resistance or expenditure of power, as a hydroplane, aeroplane pontoon or boat otherwise driven. 10 My invention is mainly intended to provide a construction of boat which is driven at high speed with minimum power; said results being obtained by a special construction of the bottom and sides of the boat so that the squatting or settling of the stern 15 20 due to the displacing action of the propeller is entirely overcome by said construction for neutralizing said action and causing the hull to lift and glide freely over the water. For simplicity the bilge or chine lines are herein referred to as knuckle lines.

My invention is based on the fact that the volume of water displaced by the propeller is approximately equal to that displaced by the boat's bow entrance through the water 30 35 40 45 50 which bow displacement by my construction is efficiently utilized in replacing the displaced propeller volume thereby overcoming this heretofore vital hindrance to the speed of boats. My construction also utilizes said bow displacement or bow wake in such a manner that in rough water any quantity of air passing under the boat is effectively diverted from propeller by the longitudinal middle bottom section under the stern end of which the propeller functions. My steering mechanism comprises a rudder for turning in each direction, one placed to either side of the stern and with the upper edges of the blades tilted at an angle toward the center line of the boat so that by actuating the outward rudder from the direction of turning the rudder lifts and at the same time skids the stern of the boat around. The design covered by my invention has further features; of extreme strength for the weight of said construction and one of extreme simplicity which is easily built.

My invention includes the novel features of construction hereinafter described, the 55 said invention being defined by the claims appended hereto.

The preferred embodiment of my invention is illustrated in the accompanying drawing, in which,

Figure 1 is a side elevation.

Fig. 2 is a plan view.

Figs. 3 to 7 are respective sections in the correspondingly numbered section lines of Fig. 1.

Fig. 8 is a rear elevation.

Referring by reference characters to this drawing A designates the hull of the boat and A' is the bow and A² is the stern. A³ designates the keel and on each side of this 70 keel I provide a concaved portion a, this concaved portion extending practically the full length of the bottom with x-x' and y-y' the knuckle or chine lines.

In my preferred embodiment as shown in 75 the drawings the bow is square and inclines downwardly and rearwardly to the point indicated at a' and from this point the keel and chines take the same curve downwardly and rearwardly for a suitable distance, preferably to the point indicated by the section line 4-4 from which point it runs substantially straight or with a slight upward curve to the bottom of the stern section or board A². Fig. 2 shows that the 80 85 90 95 keel lines and the knuckle or chine lines are in parallel vertical planes. Also in Fig. 1 the knuckle and keel lines being in the same curve, are in the same straight lines transversely. The two concaved sections a are deepest at approximately the point indicated by the section line 4-4 and grow shallower as they approach the bow and stern, or in other words the center line of the concavities or channels in the stern run in a substantially straight line from the point a' to the bottom of the stern board or section indicated at a².

For the steering of my improved boat I provide a pair of rudders B on rudder stems b, one placed to either side of the stern substantially in line with the centers of the inverted V portions and with the said stems inclined upwardly and inwardly toward the center line of the boat.

Any suitable means may be provided for

propelling the boat, such for example as a gas engine indicated conventionally at C operating the propeller D through the intervening propeller shaft E in the usual or desired manner.

Having thus described my invention what I claim is:

1. A boat hull having a V-shaped bottom portion intermediate of two inverted V-shaped portions, extending substantially the entire length of the hull, the angles of the V's gradually flattening toward the stern.
2. A boat hull having a V-shaped portion intermediate of two inverted V-shaped portions extending substantially the entire length of the hull, the angles of the V's progressively flattening from an intermediate portion toward the stern.
3. A boat hull having on its bottom a V-shaped portion intermediate two inverted V-shaped portions which gradually flatten toward the stern, the knuckle and keel lines formed by said portions being in parallel vertical planes.
4. A boat hull having on its bottom a V-shaped portion intermediate two inverted V-shaped portions which gradually flatten toward the stern, the knuckle and keel lines formed by said portions being in substantially parallel vertical planes and being in the same straight line at any transverse section.
5. A boat hull having a convex bottom portion intermediate two concave portions extending substantially the full length of

the hull, said portions gradually flattening from an intermediate point toward the stern.

6. A boat hull having on its bottom a longitudinal convex portion intermediate two concave portions which gradually flatten toward the stern, the knuckle and keel lines formed by said portions being in parallel vertical planes.

7. A boat hull having on its bottom a longitudinal convex portion intermediate two concave portions which gradually flatten toward the stern, the knuckle and keel lines formed by said portions being in substantially parallel vertical planes and being in substantially the same straight line at any transverse section.

8. A boat hull having a convex bottom portion intermediate of concave portions extending substantially the full length of the hull and gradually flattening toward the stern, and a propeller functioning under the lowest point of the convex portion in proximity to the stern.

9. A boat hull having a convex bottom portion intermediate of two concave portions extending substantially the full length of the hull and gradually flattening toward the stern, and a pair of rudders mounted approximately in line with the centers of the convex portions and inclined toward the center line of the hull.

In testimony whereof, I affix my signature.

STATES LEE LEBBY.
